UNITED STATES PATENT OFFICE

2,388,295

MUTUAL COUPLING

Richard F. Shea, Fairfield, Conn., assignor to
General Electric Company, a corporation of
New York

Application July 2, 1943, Serial No. 493,317

6 Claims. (Cl. 171—119)

My invention relates to radio receiving apparatus and, in particular, to circuit coupling arrangements for such apparatus.

It is well known in radio receivers to use magnetic body members of compressed powdered iron particles as housings and cores for transformers of radio frequency currents. From a manufacturing point of view, it is desirable to provide in such a transformer molded cores and pole pieces of a standard size and shape so that the transformer windings may be quickly and easily placed in operating position and that adjustment of the self inductance of individual windings may be accomplished by means of a single tuning core for each winding, the mutual inductance being established principally by the geometric proportions of the housing, pole pieces and cores. When unitary housings for the windings of the transformers are produced in large quantities, it is impossible to obtain the uniformity of sizes and materials necessary for the critical value of mutual inductance required for radio frequency transformers. Accordingly, it is an object of my invention to provide an improved mutual coupling arrangement for a radio frequency transformer.

It is another object of my invention to provide an improved coupling arrangement for a radio frequency transformer in which adjustment of the mutual inductance of the transformer windings may be effected easily and accurately during the initial tuning of the receiver circuits.

A further object of my invention is to provide an improved link coupling for the windings of a radio frequency transformer having a unitary powdered iron body member.

It is a still further object of my invention to provide an improved link coupling arrangement for a radio frequency transformer which likewise functions to shield adjacent receiver circuits from the high frequency fields surrounding the magnetic structure of the transformer.

One of the features of my invention is the use, in conjunction with the unitary powdered iron structure of a radio frequency transformer, of a single turn winding encircling the magnetic structure and the windings of the transformer and adjustable to the position required to give a desired value of mutual inductance for the transformer.

The features of my invention which I believe to be novel are set forth with particularity in the appended claims. My invention itself, however, both as to its organization and method of operation, together with further objects and advan-

ages thereof, may best be understood by reference to the following description taken in connection with the accompanying drawing, in which Fig. 1 is a side elevation view, partly in section, of a transformer embodying my invention; Fig. 2 is a plan view of Fig. 1 along the line 2—2; and Fig. 3 is a side elevation view of a modification of the transformer arrangement of Fig. 1.

Referring to Fig. 1, I have shown a radio frequency transformer comprising a main body member 10 having a pair of recesses 11 and 12 therein, in which are located a primary winding 13 and a secondary winding 14, the inductance of the individual windings being adjusted respectively by means of tuning cores 15 and 16. The main body member 10 is preferably a unitary structure formed by molding or compressing and machining powdered iron particles, the recesses 11 and 12 appearing as substantially cylindrical holes in this unitary body member. These recesses are separated by a central wall 17 of the body member. A longitudinal cross section of the body member 10 thus is in the form 25 of a T having, in addition to the central wall 17, end walls 18 and 19 and a base portion 20.

The cylindrical recesses 11 and 12 have centrally located openings in their bottom walls surrounded by a shoulder portion 21 for receiving 30 tubular coil forms 22, 23, upon which are wound the windings 13, 14. The upper or open ends of the recesses 11 and 12 are likewise provided with shoulders 25 for receiving the circular closure members or pole pieces 26, 27.

35 The unitary transformer structure thus far described may be supported from a radio chassis 30 by means of a bolt 31 which passes through the central wall 17 of the body member 10. The chassis 30 may have a pair of openings 32, 33 40 whose positions correspond to the positions of the windings 13, 14 within the transformer. A terminal board 35 of any suitable insulating material, preferably is clamped between chassis 30 and the body member 10 by means of bolt 31 and 45 nut 36 and has riveted thereto a plurality of terminal posts 38 to which are attached the leads 39 from the transformer windings. The terminal board 35 likewise functions to support the tuning cores 15 and 16 in an adjustable position within the tubular forms 22, 23 by means of the tubular nuts 40, 41 riveted to the terminal board and in threaded engagement with screws 42, 43, embedded at their lower ends, respectively, in cores 15, 16. The cores 15, 16 are likewise provided with slots 44, 45 at their lower ends so that

the position of these tuning cores within the transformer windings may be adjusted in the usual manner by a screw driver.

In the transformer arrangement thus far described, the self-inductance of the individual windings 13, 14 is quickly and easily adjusted in the usual manner by means of the powdered iron tuning cores 15, 16. The mutual inductance of the windings in this unitary transformer structure is established principally by the geometric proportions of the walls 17, 18, 19 of the magnetic body member 10, the thickness of the pole pieces 26, 27, and the thickness of the bottom walls 20 and the cross sectional area of the tuning cores 15, 16. While this mutual inductance may be controlled to a large extent by variation in design of the transformer, in actual production of transformers of this arrangement certain inevitable variations from desired values of mutual inductance are obtained, which variations are considerably greater than are permissible for the critical values of mutual inductance required for radio frequency transformers. In order to provide means quickly and easily to adjust the mutual inductance of the transformer windings precisely and accurately to a desired value, in accordance with my invention, a band or single turn 47 of conductive material, such as copper or aluminum, is placed around the external wall of body member 10 in a plane substantially parallel to a plane through the center line of windings 13, 14. The position of coil 47 on the external walls of the body member 10 is adjusted vertically until a desired value of mutual inductance is obtained. In general, a maximum value of mutual inductance is obtained when the coil 47 encircles the windings at their centers and this value is gradually reduced as the short-circuited turn 47 is varied vertically up or down from this position.

The operation of the transformer described will be discussed with particular reference to its use as an intermediate frequency transformer in a radio receiver of the super-heterodyne type. The windings 13 and 14 each set up magnetic lines of flux A in the body member 10, which may be considered as flowing upwardly through the respective tuning cores 15, 16, radially outwardly through the respective pole pieces 26, 27, and vertically downwardly through the end walls 18, 19 and the center wall 17. In addition to lines of flux flowing downwardly through the center wall 17, a certain proportion of lines from winding 13 flow across both closure members 26 and 27 and down through the tuning core 16. This additional flux constitutes flux lines B, which are mutual to the windings and give rise to mutual inductance between these coils. In a given transformer arrangement, as previously stated, the proportion of mutual flux to the total lines of flux is determined substantially by the dimensions of the magnetic paths between the windings.

The addition of the short-circuited winding or coupling link 47 is effective to disturb the flux arrangement thus far described. A considerable number of lines of magnetic flux A flows exteriorly of the walls 18, 19 in the space outside the body member 10 to link the short-circuited turn 47 and induce a current therein. This current, in turn, sets up lines of flux C in a direction opposing the original lines A. These lines passing through coil 13 oppose lines A therein, slightly reducing its inductance. The lines C, which pass through coil 14, however, are in the same direction as the lines B coming from coil 13

and therefore reinforce the lines B with the result that the mutual inductance of the coils is increased. In this manner the short-circuited turn 47 acts as a link coupling between the two coils. The value of the mutual inductance of the windings of the transformer is greatest when the coil 47 is in a central position on the external walls of body member 10 and decreases in substantially the same amount with a given change in position either up or down from this central point. When a desired value of mutual inductance is obtained, the coil 47 may be easily cemented, or otherwise secured, in a desired position on the outside of the transformer body 10. In a given transformer structure, it has been found that, by varying the position of coil 47 from the bottom of the side walls 18, 19 to the center of these side walls, the mutual inductance may be increased 100 per cent.

The plan view of the transformer arrangement of Fig. 1 shown in Fig. 2 illustrates the general configuration of the main body 10 and the relative sizes of the recesses 11, 12 and the walls 17, 18, 19. It also shows the manner in which the short-circuiting turn 47 is passed around the main body member 10 adjacent the external walls of this body member.

In the modification of the coupling arrangement shown in Fig. 3, the transformer body member 10 is substantially entirely enclosed in a shielding can or housing 50 of conductive material, such as copper or aluminum. The shielding can 50 is provided with suitable apertures in its bottom surface to permit the adjustment of tuning cores 15 and 16 within the individual windings 13 and 14. In order to provide means for adjusting the mutual inductance of the transformer, the shielding can 50 is provided with a vertical slot 51 which is substantially transverse to a plane through the windings within the transformer.

In adjusting the mutual inductance of the transformer arrangement shown in Fig. 3, the slot 51 is filled to a desired extent with any suitable conductive material 52, such as solder, until a desired value of mutual inductance is obtained. The housing 50 not only provides means for controlling the mutual inductance of the transformer windings without causing any substantial change in the self-inductance of the individual lines, but also functions substantially completely to shield adjacent receiver circuits from the high frequency fields surrounding the magnetic body member 10 of the transformer. In a given installation, when the body member 10 is completely shielded by the housing or can 50, the self-inductance of the individual windings is changed by less than 10 per cent, while the mutual inductance of the windings may be varied over a range of 2 to 1. The self-inductances of the windings, of course, may be readjusted to desired values by means of the tuning cores 15 and 16.

While I have shown a particular embodiment of my invention, it will of course be understood that I do not wish to be limited thereto since various modifications may be made, and I contemplate by the appended claims to cover any such modifications as fall within the true spirit and scope of my invention.

What I claim as new and desire to secure by Letters Patent of the United States is:

1. In combination, a radio frequency transformer comprising a body member of magnetic material having a plurality of recesses therein, said recesses being separated by a wall of said

body member, each of said recesses having a corresponding winding of said transformer positioned therein, and magnetic closure members for said recesses, and a continuous loop of conductive material supported in fixed position adjacent the external walls of said body member and encircling said windings to provide desired mutual coupling thereof.

2. In combination, a radio frequency transformer comprising a body member of magnetic material having a plurality of recesses therein, said recesses being separated by a wall of said body member, each of said recesses having a corresponding winding of said transformer positioned therein, and means for adjusting the mutual inductance of said windings, said means comprising a single loop of conductive material supported adjacent the external surface of said body member in a position encircling said windings.

3. In combination, a radio frequency transformer comprising a body member of magnetic material having a pair of recesses therein, said recesses being separated by a wall of said body, each of said recesses having a winding of said transformer positioned therein, and means for adjusting the mutual coupling of said windings and for shielding said body member, said means comprising a casing of conductive material substantially enclosing said body member, said casing having in one wall thereof a slot substantially

transverse to a plane through said windings, said slot being of a length sufficient to give a desired coupling of said windings.

4. In combination, a radio frequency transformer comprising a body member of magnetic material, a pair of windings positioned within said body member, and means for adjusting the mutual inductance of said windings comprising a loop of conductive material supported adjacent the external surface of said body member in a position encircling said windings.

5. A radio frequency transformer comprising a unitary magnetic body member, a pair of windings positioned within said member and separated by a wall thereof, and means for adjusting the mutual inductance of said windings comprising a continuous loop of conductive material supported adjacent the external surface of said body member in a position encircling said windings.

6. A radio frequency transformer comprising a unitary magnetic body member, a pair of substantially coplanar windings positioned within said member and separated by a wall thereof, a continuous loop of conductive material encircling said body member and substantially parallel with said windings, said loop being secured to the external surface of said body member in a predetermined position to obtain a desired value of mutual inductance of said windings.
